UNITED STATES PATENT OFFICE.

EMERSON D. SAWYER, OF CHICAGO, ILLINOIS.

YIELDABLE BARRIER.

Application filed May 16, 1923. Serial No. 639,365.

My invention relates to certain novel improvements in yieldable barriers and has for its principal object the provision of an improved construction of this character which will be highly efficient in use and economical in manufacture. The present invention constitutes an improvement over the construction disclosed in my prior application filed in the United States Patent Office 5 on or about December 27, 1921, bearing Serial 10 No. 525,236, for yieldable barriers.

The present invention relates especially to the spacer box within which is arranged mechanism for controlling the paying out 15 of the reserve cables operatively connected to the barrier. The construction of the mechanism is of such nature that the parts constituting the same are built to withstand that which is expected of devices of this 20 character such as sudden jerks and impacts and the construction and arrangement of parts are of such nature that they will work with unitary accuracy during the operation of the barrier when struck by a vehicle. 25 Heretofore in constructions of similar character during the paying out of the reserve cables, mechanism such as counter weights were employed to oppose the paying out of the cables, these counter weights being 30 adapted to move between limbs of a U-shaped or fork shaped member, the limbs of which opposing such movement of the counter weights and thereby bringing the paying out of the reserve cables under control. This 35 construction has not proven to be satisfactory and it is therefore one of the objects of the present invention to provide mechanism to oppose the paying out of the reserve cables and which will permit automatic recoil of 40 the same after the object striking the barrier has been removed.

Other objects will appear hereinafter.

The invention consists in the combinations and arrangements of parts hereinafter 45 described and claimed.

The invention will be best understood by reference to the accompanying drawings forming a part of this specification, and in which,

Fig. 1 is a face view of the carriage or spacer box embodied in the invention;

Fig. 2 is a sectional view of the same taken substantially on line 2—2 of Fig. 3;

Fig. 3 is a sectional view taken substantially on line 3—3 of Fig. 2;

55

Fig. 4 is a sectional view taken substantially on line 4—4 of Fig. 1;

Fig. 5 is an edge view of certain spring members embodied in the invention;

Fig. 6 is a side view of the spring member 60 illustrated in Fig. 5;

Fig. 7 is a sectional view taken substantially on line 7—7 of Fig. 1;

Fig. 8 is a fragmentary sectional view taken substantially on line 8—8 of Fig. 2;

65

Fig. 9 is a fragmentary side elevational view of the yieldable barrier embodying the invention.

Referring particularly to Fig. 9, 15 indicates a hollow column or standard divided into compartments 15' and 16' by a vertical partition 17', 16 indicates a barrier, 17 indicates a side walk arm and 18 indicates the foundation of the column 15. The face 19 70 of the column is open longitudinally as at 20 for reasons to be more fully understood from the description to follow.

In practical use there are employed two 75 such columns 19 one on each side of the road way along which the vehicle to be stopped passes and the barrier 16 when lowered into the position illustrated in Fig. 9 extends across the road way.

Arranged to move longitudinally within 80 each of the columns within the compartment 15' of each, is a spacer box or carriage A having means of attachment to the ends of a sprocket chain 21 as indicated at 21', said means at one end of the spacer box includes 85 a turn buckle (a) fixed to the box at that end by a bolt (b) passing through lugs (c) and at the other end said means includes a spring controlled U-shaped member (d) having its limbs taken through an integral portion (e) of the spacer box. The sprocket chain 90 passes over sprocket gears 22 arranged at the upper and lower end of the column and operative by suitable motive power (not shown).

The mechanism for moving the spacer box 95 is embodied in a companion application filed in the United States Patent Office on even

date and for the construction and arrangement of such driving mechanism reference is to be had to said application.

The opposite ends of the barrier 16 are operatively connected to reserve cables 23 and 24 which pass into the adjacent spacer box through openings 25 formed in leaders 26 and coiled around drums 27 and 28 respectively, said cables being fixed to the drums by suitable means such for example as indicated at 22'. As best shown in Fig. 7 the reserve cables are formed flat, this being accomplished by binding the single cables together in a suitable manner, and the advantage rests in the fact that the strength of the cables is increased and the same will recoil on the cable drums more evenly and smoothly. It will be noted that the strands of cable (h) are wound opposite the strands of cable (g) as indicated. The arrangement is preferred because when the cables are taut they will transmit resistance against each other due to the tendency to unwind against each other.

25 As the spacer boxes are of similar structure I will detail the construction of one and it is to be understood that the construction of one applies to the construction of the other.

In this connection the cable drums 27 and 28 are keyed to shafts 29 and 29' mounted in suitable bearings 30 and operatively connected by gears 31.

35 In the compartments 16' a counter weight 32 is arranged to move longitudinally and is supported by a cable 33 which passes over a sheave wheel (not shown) at the upper end of the column and leads downwardly through an opening 34 formed in the top of the spacer box and coiled around a drum 27' forming an integral part of the cable drum 27.

40 Adjacent the drum 27' is a disc 35 keyed to the shaft 29', and provided with spiral grooves in its outer face as at 36. An arm 45 37 is arranged within the box and pivoted thereto as at 38 and is pivotally connected to an adjustable link 39 as at 40. The free end of the arm 37 carries a block 41 mounted to rock on a pintle 42 and provided with a bevelled finger 43 working in the spiral grooves 36. The lower end of the link 39 is pivoted to a flat plate 44 as at 45 and the flat plate 44 is pivoted to a fixed support 46 as at 47. The fixed support is carried 50 by a transverse shaft 48 to which one end of a brake band 49 is fixed. The brake band 49 extends around a brake drum 50, of suitable construction, and has its free end operatively connected to the plate 44 as 55 at 51.

60 The operation of the construction so far described is such that upon rotation of the disc 35 the finger 43 working in the spiral grooves by following the grooves away from the center of the disc, actuates the arm 37

to tighten the brake band 49 around the brake drum 50. In rotating in the opposite direction the finger working in the spiral grooves moves away from the peripheral edge of the disc and actuates the arm 37 to loosen the brake band and permit free movement of the brake drum.

The brake drum is mounted on a hub 52 forming an integral part of the drum 28 and is free to idle on the hub. Between the brake drum and the cable drum 28 is a ratchet 53 for engagement with spring controlled pawls 54 and forms an integral part of the brake drum as best shown in Fig. 2. The springs of the pawls 54 are indicated 80 at 55 and the pawls are carried on studs 56 carried by the cable drum 28.

When the cable drums 27 and 28 rotate in a direction to permit paying out of the reserve cables the pawls are in engagement with the ratchet and rotate the brake drum and at the same time the disc 35 rotates and due to the operation of the arm 37 the brake band is gradually tightened around the brake drum. When the cable drums 27 and 28 rotate in the opposite direction the brake drum idles on the hub 52, and due to the operation of the arm 37 through the medium of the finger 43 the brake band is loosened.

It will be seen from the foregoing description that I provide a brake mechanism for controlling the paying out of the reserve cables which will be automatically released when the cables are recoiled on the cable drums, the operation being assured through the medium of the finger working in the spiral grooves and actuating the arm 37 to release the brake band. This construction does away with the necessity of employing hand operating means for releasing the brake mechanism. The recoil of the reserve cables is brought about through the medium of the counter weight herein referred to and which by reason of the fact that the counter weight is connected to the drum 27' by cable 33, the cable is coiled around the drum when the reserve cables are paid out at the time the barrier is struck. And after removal of the object striking the barrier the drum 27' is rotated by the counter weight, and the drums 27 and 28 being operatively connected together are at the same time rotated and the reserve cable recoiled thereon.

In connection with the spacer box in order to lessen friction when the spacer box moves up and down within the column, I mount at the upper end and lower end of the box, rollers indicated at 56. These rollers are carried on shafts 57 which are under the influence of springs 58 and provided with transverse slots 59 through which bolts 60, carried by ears 61 pass, the ears 61 form an integral part of brackets 62. The outer faces of the brackets have recessed portions indicated at 63 for the reception of the leaf 130

portions 64 of the spring members 58. Each of the spring members 58 include two leaf springs indicated at 63' and 64' having curved portions 65 abutting together as at 66 and fixed in such position by a rivet 67. The outer ends of the leaf portions 64' abut the adjacent shaft 57 which is preferably rectangular in shape. By this arrangement the shaft is permitted to move toward the 10 spacer box and is forced outwardly therefrom against the adjacent inner surfaces of the column by the spring members. The primary object of the adjustability of the rollers is to provide a cushioning means for 15 the spacer box when an impact is transmitted thereto through the barrier when struck by a vehicle. When this action takes place the spacer box by the provision of the springs is stopped from suddenly striking 20 against the adjacent walls of the column. The rollers permit easy movement of the box when raised or lowered within the compartment, and the advantage of such arrangement can be appreciated when it is taken 25 into consideration the degree of durability of a device of the character herein described.

Along the inner surfaces of the wall portion 19 adjacent the opening 20 on one side thereof I arrange a friction pad indicated at 30 68 and formed of suitable material, the pad extends from the bottom of the column to about a distance of six feet more or less thereabove. This arrangement is such that when the barrier 16 is struck by a vehicle 35 the spacer box comes into contact with the pad and when such action takes place upward movement of the spacer box is opposed.

In connection with each of the leaders indicated at 26 which is provided with a hub portion indicated at 26' fitting into an enlarged opening 28', I have found by experience that the reserve cables when paid out of the spacer box wear down the curved surface indicated at 69 and opening 25 and when the reserve cables are retarded the opening 25 is not in alignment with the groove of the cable drum on which the cable is wound and causes the cable to slip over the edges of the drum. To overcome this, 50 I prefer to mount each of the leaders in such a manner that the same can be adjusted and this is accomplished by providing elongated slots indicated at 70 through which bolts 71 pass, the bolts 71 being screw threaded in the adjacent wall of the spacer box. By loosening the bolts 71 the leader can be shifted either to the right or left as the case may require.

As indicated in Fig. 1 an opening 72 is 55 formed in the wall 73 of the spacer box. This provision permits access to the interior of the box for purposes of adjusting the adjustable link 39.

By reference to the foregoing description it is apparent that I accomplish many advan-

tages over the constructions of similar devices that are now commercially in use and I also provide an arrangement and construction of parts which will withstand the rough usage expected of a device of this character and the 70 parts can be manufactured at an economical cost.

While I have illustrated and described the preferred form of construction for carrying my invention into effect, this is capable of 75 variation and modification without departing from the spirit of the invention. I, therefore, do not wish to be limited to the precise details of construction set forth, but desire to avail myself of such variations and 80 modifications as come within the scope of the appended claims.

Having described my invention what I claim as new and desire to secure by Letters 85 Patent, is:

1. A device of the class described comprising a spacer box; coils of reserve members within the box; an impact receiving member connected with said reserve members, said reserve members being adapted to 90 be paid out of the box by movement of the impact receiving member; a brake drum operatively connected with said reserve members, a band for said drum; and automatic means for applying said band to said 95 drum as the reserve members pay out and releasing said band from said drum as said impact receiving member returns to position.

2. A device of the class described comprising a spacer box; coils of reserve members within said box; an impact receiving member operatively connected with said reserve members, said reserve members being adapted to be paid out of the box by movement of the impact receiving member; a 100 brake drum operatively connected with said reserve members; a brake band for said drum; means for recoiling the reserve members; and automatic means for applying said 105 brake band as the reserve members pay out and releasing said brake band as the reserve members are recoiled.

3. A device of the class described comprising a spacer box; winding drums in said box; reserve members wound on said drums; an impact receiving member connected with said reserve members, said reserve members being adapted to be paid out by movement of the impact member; means for recoiling the 115 reserve members on said drums; a brake 120 drum operatively connected with said coiling drums; a brake band for said brake drum; a member operatively connected with one of said coiling drums and having spiral grooves in its face; and a member connected to operate in said grooves and operatively connected with said brake drum.

4. A device of the class described comprising a spacer box; winding drums in said 125 box; reserve members coiled on said drums;

- an impact receiving member operatively connected with said reserve members, said reserve members being adapted to be paid out by movement of the impact member; means 5 for recoiling the reserve members; a brake drum operatively connected with said winding drums; a brake band for said brake drum; a member operatively connected with said winding drums and having operating 10 grooves formed therein; and an arm connected to be operated by said grooves and operatively connected with said brake band.
5. A device of the class described comprising a spacer box; drums arranged in 15 the box and operatively connected together; coils of reserve members on said drums; a rewinding member coiled on said drums and connected with a rewinding weight; an impact receiving member operatively connected with said reserve members; a member 20 having spiral grooves in its face and operatively connected with one of said drums; a brake band; and an arm operable by said grooves and operatively connected with said 25 brake band.
6. A device of the class described comprising a spacer box having coiling drums arranged therein and operatively connected together; reserve members coiled on said 30 drums; an impact receiving member connected with said reserve members; a recoiling member coiled on one of said drums; a counterweight operatively connected with said recoiling member; a brake drum on 35 the hub of said coiling drums; a brake band for said brake drum; and means operable by the rotation of said coiling drums for operating said brake band.
7. A device of the class described comprising a spacer box having coiling drums arranged therein and operatively connected together; reserve members coiled on said 40 drums; an impact receiving member connected with said reserve members; a recoiling member coiled on one of said drums; a counterweight operatively connected with 45 said recoiling member; a brake drum on the hub of one of said coiling drums; a brake band for said brake drum; a member having 50 grooves formed therein and operatively connected with one of said coiling drums; and an arm operable by said grooves and operatively connected with said brake band.
8. A device of the class described comprising a spacer box having coiling drums arranged therein and operatively connected together; reserve members coiled on said 55 drums; an impact receiving member connected with said reserve members; a recoiling member coiled on one of said drums; a counterweight operatively connected with 60 said recoiling member; a brake drum on the hub of one of said coiling drums; a brake band for said brake drum; a member operatively connected with one of said drums and
- having spiral grooves in its face; and a brake arm operable by said grooves and operatively connected with said brake band.
9. A device of the class described comprising a spacer box; winding drums in the box and operatively connected together; a brake drum having a pawl and ratchet connection with one of said winding drums; a brake band for said brake drum; and automatic means controlled by said winding drums for operating said brake band.
10. A yielding barrier comprising a hollow column; a carriage mounted for movement in the column; an impact receiving member mounted on said carriage; a friction pad for engagement with said carriage when moved toward a wall of the column; and rollers on said carriage and operating on said column.
11. A yielding barrier including a hollow column; a carriage operating in said column; an impact receiving member carried by said carriage; and spring rollers on said carriage operating on a wall of the column and permitting movement of the carriage toward the column under strain.
12. A yielding barrier including a hollow column; a carriage operating in said column; an impact receiving member carried by said carriage; a friction pad in said column arranged to engage said carriage when moved toward a wall of the column; and spring held rollers on said carriage operating on said wall of the column and arranged to permit contact with said friction pad under impact.
13. A yieldable barrier including a hollow column, an impact receiving member, & spacer box arranged for movement within the column and having openings therein drums arranged in said spacer box and operatively connected together; adjustable leaders mounted in said openings, and reserve members coiled on said drums, passing through said leaders and operatively connected to the impact receiving member, said reserve members being adapted to be paid out through said leaders upon movement of the impact receiving member.
14. A yielding barrier comprising columns at opposite sides of the roadway; carriers arranged to move vertically in said columns; drums on said carriers; flexible reserve members coiled on said drums; an impact receiving member extending across the roadway and operatively connected with said reserve members; and a brake resisting unwinding of said drums.
15. A yielding barrier comprising columns at opposite sides of the roadway; carriers arranged to move vertically in said columns; drums on said carriers; flexible reserve members coiled on said drums; an impact receiving member extending across the roadway and operatively connected with

said reserve members; a brake resisting movement of said reserve members; and automatic means for releasing said brake at the end of the movement of said barrier.

16. A yielding barrier comprising columns at opposite sides of the roadway; carriers arranged to move vertically in said columns; drums in said carriers; flexible reserve members coiled on said drums; an impact

receiving member extending across the roadway connected with said reserve members; and automatic means for returning the barrier to initial position after movement along the roadway by impact of a vehicle. 10

In testimony whereof I have signed my ¹⁵ name to this specification.

EMERSON D. SAWYER.
